(57) **CLAIM**

The ornamental design for a smoking guide, as shown and described.

DESCRIPTION

FIG. 1 is a perspective view of a smoking guide, showing my new design;

FIG. 2 is a front elevational view thereof;

FIG. 3 is a back elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The dot-dash broken lines in the drawings define the boundaries of the claimed design and form no part thereof. The short dash-dot broken lines in the drawings depict environment and form no part of the claimed design.

1 Claim, 5 Drawing Sheets(56)

TURKEY (Whole Bird)	225°F	45 mins/lb	165°F	PECAN
TURKEY BREASTS/LEGS	250°F	3-4 hrs	165°F	
SEAFOOD				
FISH(FILETS) 2 LBS	225°F	35-45 mins	145°F	
SALMON/TROUT	225°F	3-4 hrs	140°F	ALDER

REMINDEEE: Always cook to temp, not time. All guidelines for temps/times given are recommendations only. Always use your own best judgement.

Some meats benefit from finishing at higher temps to develop a nice bark or crispy skin.
